UNITED STATES PATENT OFFICE.

FREDERICK A. GLINES, OF CAMBRIDGE, MASSACHUSETTS.

BICYCLE-BELL.

SPECIFICATION forming part of Letters Patent No. 595,057, dated December 7, 1897.

Application filed March 17, 1897. Serial No. 627,983. (No model.)

To all whom it may concern:

Be it known that I, FREDERICK A. GLINES, a citizen of the United States, residing at Cambridge, in the county of Middlesex and State 5 of Massachusetts, have invented a new and useful Bicycle-Bell, of which the following is a full, clear, and exact description.

The object of this invention is the construction of a bell for bicycles which shall be automatically rung by the resistance of the air caused by the vehicle's progress and which may be thrown out of gear and made silent whenever desired.

In the drawings forming part of this specification, Figure 1 is an elevation, partly in section, of my bell and actuating mechanism. Fig. 2 is a cross-section of the same through xx in Fig. 1. Fig. 3 is a detail sectional view drawn on a larger scale. Fig. 4 is a detail 20 top view of a part thereof, and Fig. 5 is a longitudinal section of a modification.

The main portion of my invention comprises the wind-wheel m , the bell a , hammer h , the supporting-stud c , and the clamp for 25 attaching the whole to the handle-bar or steering-head of a bicycle. Said clamp consists of the two parts e e' , adapted to clasp the handle-bar or similar part and clamped together by the bolts e^2 . The clamp-section e 30 is provided with the boss d , into which is rigidly fastened, either by screw-threads or brazing, &c., the tubular stud c . Movable upon said stud is the sleeve b , carrying the bell or gong a and provided with the finger-piece b'

35 for retracting the same against the pressure of the coiled spring f . For holding said sleeve in this position of retraction the sleeve is given the lock-slot b^2 , into which extends the pin b^3 from the stud c . Said slot being of the 40 approximately L shape as shown in Fig. 4, a combined pull and rotative pressure applied to the finger-piece b' insures the entrance of the pin b^3 into the locking portion of said slot and the consequent retention of the sleeve 45 in its desired position of retraction. The object in thus reciprocating the sleeve b , and consequently the gong mounted thereon, is to render the latter mute or to put it into sonorous vibration. The manner in which this 50 is effected is as follows:

Within the stud c is the slender shaft g , carrying the wind-wheel m . Rigidly connected

with said shaft and wheel is the arm h' , having the striking disk or hammer h in its bifurcated extremity. The axial pin h^3 of this 55 disk is loosely held in the slotted bearings h^3 in said arm and thereby permitted a limited radial play. As said hammer rotates with the wind-wheel m it comes in contact with the rib a' within the gong a and causes the same 60 to sound. By drawing back the gong, however, its edge is brought out of the range of the hammer and the latter rotates without possibility of striking the rib a' . Hence no matter how rapidly the wind-wheel now re- 65 volves the bell is utterly mute.

The wheel m is usually constructed from thin sheet metal and is retained in place upon the shaft g by means of the shoulder k' and nut k . The boss h^4 is for the purpose of 70 counterweighting the hammer and arm h .

The shaft g is retained in the stud c by having its outer portion larger in diameter than the remainder and attaching to the end of the stud a collar c' , abutting against the shoulder thus formed. The inner end of the shaft 75 is made conical, as g^2 , and bears against the recessed plug d' .

In Fig. 5 I show my preferred arrangement of the shaft. Here there is no collar c' , but 80 the shaft is held in place by the conical head g^2 being of larger diameter than the shaft and bearing between the end of the stud c and the bottom of the socket d^2 , in which said stud is secured.

In using this bicycle-bell it is fastened upon the handle-bar or other convenient part of the frame, with the finger-piece b' uppermost and the rib a' consequently at the lower side of the gong. If the rider wishes the bell to 90 sound, he gives the finger-piece a side hit, the locking-slot b^2 is released from the pin b^3 , the sleeve and gong slide forward, the rib a' comes into the path of the hammer, and the speed of the bicycle through the air-pressure 95 upon the wind-wheel produces the desired result. The rider can now speed upon his way without further attention to the bell, which will continue its resonant vibrations so long as the bicycle is in motion. If now 100 the rider comes to an unobstructed stretch of road and no longer wishes his bell to ring, he simply gives a pull to the finger-piece b' and locks the gong out of contact with the ham-

- mer. The wind-wheel, however, continues its whirling, attracting the attention of passers-by to the novel and attractive sight, and ready at an instant's notice to again resume its audible duty. The advantages in thus permitting the wind-wheel constant rotation and putting it into and out of gear by removal of the gong from the path of the actuating devices are, first, that no shock is given to the mechanism by an instantaneous stopping of the wheel's motion and no strain is given by thus holding it motionless; further, the wheel being in rapid rotation the gong is loudly rung upon the instant of throwing the latter into position. Were the wheel required to work up to the required speed from a state of rest, there would be a more or less dangerous delay in setting the gong into vibration.
- 20 What I claim as my invention, and desire to secure by Letters Patent, is as follows, to wit:
1. The combination of the wind-wheel and hammer, the stud revolvably supporting the same and adapted to be secured to a vehicle, and the gong longitudinally movable upon said stud and thereby removed from or put into contact with said hammer, substantially as and for the purpose specified.
2. The combination of the wind-wheel and hammer, the stud revolvably supporting said wheel and hammer, the sleeve movable upon said stud, the gong mounted on said sleeve and having rib normally contacting with said hammer, a spring for retaining said gong in

said normal position, and a lock for fastening the said sleeve and gong away from the normal position, substantially as and for the purpose specified.

3. The combination of the wind-wheel and hammer, the stud revolvably supporting said wheel and hammer, the sleeve movable upon said stud and having finger-piece, b^1 , and locking-slot, b^2 , a pin, b^3 , projecting from said stud into said slot, the gong mounted on said sleeve and the spring for normally retaining said gong and hammer in retroacting position, substantially as and for the purpose specified.

4. In a bicycle-bell, the combination of the clamp, e , having socket, d^2 , the stud, c , secured in said socket, the shaft, g , rotatable in said stud and having bearing-head, g^2 , the wind-wheel and hammer mounted on said shaft, and the gong adapted to be rung by said hammer, substantially as and for the purpose specified.

5. In a bicycle-bell, the combination of the gong, the wind-wheel and hammer, the shaft, g , shoulder, k' , and the nut, k , and the counterweight, h^4 , substantially as and for the purpose specified.

In testimony that I claim the foregoing invention I have hereunto set my hand this 13th day of March, in the year 1897.

FREDERICK A. GLINES. [L. S.]
